Patented Aug. 9, 1921.

Inventor:
Harvey H. Wells,

By H. L. Gray Atty.

UNITED STATES PATENT OFFICE.

HARVEY H. WELLS, OF CHICAGO, ILLINOIS.

BOX.

1,387,084.

Specification of Letters Patent. Patented Aug. 9, 1921.

Application filed December 5, 1919. Serial No. 342,591.

To all whom it may concern:

Be it known that I, HARVEY H. WELLS, citizen of the United States, residing at Chicago, in the county of Cook and State 5 of Illinois, have invented a certain new and useful Improvement in Boxes, of which the following is a full, clear, concise, and exact description.

My invention relates to those boxes formed 10 of cardboard or other sheet material having rectangular sides, tops and bottoms and provided at their tops and bottoms with wing extensions instead of displaceable lids.

The invention resides in providing a box 15 tying string in such relation to the wing extensions that the string may be employed to tie the box effectively closed, the string being upon the exterior of the wings at the transverse edges thereof to prevent the box 20 from being pried open at these edges.

I will explain my invention more fully by reference to the accompanying drawing showing the preferred embodiment thereof and in which Figure 1 is a perspective view 25 of a box equipped with the string in accordance with the invention; Fig. 2 is a plan view of a bottom of the box with parts broken away; and Fig. 3 is a sectional view on line 3—3 of Fig. 2.

Like parts are indicated by similar characters of reference throughout the different figures.

The box illustrated is formed of sheet material having four rectangular sides 1—1, 35 2—2 whose top and bottom edges respectively define rectangles. The opposite sides 1 of the box are formed with foldable wing extensions 3 at the top and bottom edges of these opposite box sides, these wing extensions 40 projecting inwardly toward each other upon the top of the box and upon the bottom of the box. The remaining opposite sides 2 of the box are formed with other foldable wing extensions 4 at the top and 45 bottom edges of these box sides 2, these wing extensions projecting inwardly toward each other and overlapping at their inner or free ends upon the top of the box and upon the bottom of the box, the first aforesaid wing 50 extensions 3 being inclosed by the overlapping wing extensions 4. Each outermost

one of the overlapping wing extensions has four holes 5, 6, 7 and 8 distributed along its free end. A string 9 circumscribes the box. It passes over those top and bottom corners 55 10 of the box that are at the top and bottom edges of the aforesaid sides 1 from which the first aforesaid wing extensions 3 project. The string passes through the holes 5 and 8 that are nearest said top and bottom box corners into place between the corresponding overlapping wings, the string also passing through the remaining holes 6 and 7 to be upon the exterior of the overlapping wings. The string, where it passes 60 through these holes, is in one plane but the string is desirably also passed around the box in another plane at right angles to the first. In the latter passage of the string it is desirably disposed between the part of the 65 string that passes through the holes 6 and 7 and the box to keep this part of the string from slipping off. The loose ends of the string may be tied together and sealed by a seal 11.

Having thus described my invention I claim as new and desire to secure by Letters Patent the following:

The combination with a box formed of sheet material and having four rectangular 80 sides whose top and bottom edges respectively define rectangles, two opposite sides of the box being formed with foldable wing extensions projecting from the top and bottom edges thereof, the remaining opposite 85 sides of the box being also formed with foldable wing extensions projecting from the top and bottom edges of these remaining box sides, the latter wing extensions upon the top of the box and also those upon the bottom of the box overlapping each other at their free ends, the first aforesaid wing extensions being inclosed by said overlapping wing extensions, an outermost one of the latter wing extensions having four holes distributed along its free end; of a string circumscribing the box and passing in one plane over those top and bottom corners of the box at the top and bottom edges of those 90 opposite sides of the box from which the first aforesaid wings extend, this string 95 passing through the holes nearest the ad-

5 jacent sides of the box into place between the corresponding overlapping wings and through the remaining holes to be upon the exterior of these wings, said string also being passed about the box in another plane substantially at right angles to the first and between the box and the portion of the string

that is upon the exterior of the box and between the aforesaid remaining holes.

In witness whereof I hereunto subscribe to my name this seventh day of November, A. D. 1919.

HARVEY H. WELLS.
